The ornamental design for an arterial blood pressure transducer module clip, as shown and described.

DESCRIPTION

FIG. 1 is a front, bottom perspective view of an arterial blood pressure transducer module clip showing my new design.

FIG. 2 is a front, top perspective view of the arterial blood pressure transducer module clip.

FIG. 3 is a side view of the first side of the arterial blood pressure transducer module clip.

FIG. 4 is a side view of the second side of the arterial blood pressure transducer module clip.

FIG. 5 is a top view of the arterial blood pressure transducer module clip.

FIG. 6 is a bottom view of the arterial blood pressure transducer module clip.

FIG. 7 is a front view of the arterial blood pressure transducer module clip.

FIG. 8 is a rear view of the arterial blood pressure transducer module clip; and,

FIG. 9 is a top perspective view of the arterial blood pressure transducer module clip.

Throughout the Figures, aspects shown in broken lines are not considered a portion of the claimed ornamental design.
